UNITED STATES PATENT OFFICE.

CHARLES E. CAMPBELL, OF LYNN, MASSACHUSETTS.

TIME-SWITCH.

984,191.

Specification of Letters Patent. Patented Feb. 14, 1911.

Application filed October 31, 1908. Serial No. 460,399.

To all whom it may concern:

Be it known that I, CHARLES E. CAMPBELL, a citizen of the United States, residing in Lynn, in the county of Essex and State of Massachusetts, have invented an Improvement in Time-Switches, of which the following description, in connection with the accompanying drawings, is a specification, like letters on the drawings representing like parts.

The present invention relates to a time switch, the purpose of the invention being to arrange the mechanism so that a powerful switch, capable of controlling heavy currents, can be accurately operated by a delicate clock-work mechanism, without the expenditure of sufficient power to disturb the operation of the clock.

In controlling heavy currents, it is necessary to employ a switch having large contact surfaces, and the so-called knife blade switch has been found to be the most practicable for this purpose. In a knife blade switch, however, the contact portions are of large area, and the frictional resistance to the opening and closing of the switch is so large that it requires considerable power to operate the switch effectually. Furthermore, it is necessary to have a wide opening and a rapid movement in opening the switch so as to prevent the formation of an arc, and consequent destruction of the contacts. It is necessary, therefore, if such a switch is to be controlled by clock work mechanism, to employ intermediate actuating devices which can be controlled by the expenditure of very slight power, and, at the same time, are capable of exerting sufficient power to operate the switch. In accordance with the invention, therefore, the movable member of the switch is provided with a powerful spring so arranged as to be neutral when the switch member is substantially half way between its open and closed position, and to be placed under tension when the switch is fully closed or fully open. In either position, therefore, the spring has a tendency to act, and, if the switch is released, the movable member will be given an impulse by the spring which will tend to carry the same past the neutral position and to place the spring under tension again in the opposite direction. In order that this expedient may be utilized in connection with a tripping device, the movable member of the switch is connected by

means of a link or pitman with a rotating member which is so mounted with relation to the switch that the link or pitman will be approximately in line with the axis of the rotating member and its point of connection with the switch member when the switch is either open or closed; substantially half a revolution of the rotating member constituting a sufficient movement to carry the switch member from one extreme to the other. The rotating member, which requires a comparatively small amount of power to throw the pitman off the line and permit the main actuating spring to come into play, is provided with a light spring or equivalent motor, and is held against the action of said spring by means of a stop which is arranged to be acted upon by a movable tripping member directly connected with the clock work mechanism which affords the timing element. By this expedient, a very slight amount of power is required to release the rotating member, and comparatively little power is required to start the rotation thereof, although the spring which acts directly upon the switch is strong enough to insure the effectual opening and closing operation.

A further feature of the invention consists in arranging the apparatus so that the switch can be submerged in oil in cases where current of high voltage are to be employed.

A further feature of the invention consists in a novel construction of the tripping member which is carried by the time element or clock work whereby the said tripping member is automatically held against backward movement, although capable of forward movement for the purpose of setting the instrument to operate at the time desired.

Figure 1 is a front elevation of a time switch embodying the invention; Fig. 2 is a section, partly in elevation, taken on line a^2 of Fig. 1; Fig. 3 is a perspective view of one of the tripping members carried by the clock mechanism; and Fig. 4 is a front elevation, partly in section, showing a modification in which the switch is submerged in oil.

The switch, which is designed to control currents of high voltage, is shown as of the so-called knife-blade type, and is provided with a pivotally supported blade member a which is arranged to make contact

with a spring socket *b*, the blade entering between the sides of the socket so as to afford a large contact surface to conduct the current through the circuit indicated by the conductors 1 and 2; for example, a lighting circuit for a store. In order to open and close a switch of this type, a relatively powerful actuating device is necessary in order to overcome the friction between the 5 two members of the switch, and if the switch is to be controlled by delicate mechanism, such as clock-work of the ordinary kind, it is necessary to arrange the clock so that the clock work can be employed to set 10 a more powerful actuating device in operation, without itself performing the necessary work. It is further essential to have a large range of movement of the movable member of the switch in order to separate 15 the contacts by a wide gap, and prevent the formation of an arc during the opening of the switch. To these ends, the switch is provided primarily with an actuating spring *c* having sufficient strength to overcome the 20 frictional engagement between the switch members *a* and *b*, and to start a rapid movement of the movable member which will be continued by momentum after the spring has ceased to act. This spring is arranged 25 to be double acting, that is to say, substantially neutral in an intermediate position, and placed under stress when the movable member *a* is in either extreme position. For the purpose of starting the operation of the 30 spring *c*, the member *a* is connected with a traveling member *d* herein shown as a rotating disk arranged to be operated by means of a spring *d*², and the said disk is connected by means of a pitman *e* with the 35 switch member *a*. The relation of the parts is such that a half rotation of the member *d* acting through the pitman *e* will carry the movable member *a* of the switch from its closed to its open position, as indicated 40 in full and dotted lines, Fig. 1, and the member *d* is so controlled as to be stopped in one or the other of the positions shown, in each case the pitman *e* being substantially in line with the axis of the member *d*. 45 In each case, furthermore, the spring *c* is under tension, but is resisted by the direct pull or push upon the pitman *e*, so that the said spring has no tendency to turn the member *d*, but, on the contrary, is held 50 thereby. A slight rotary movement of the member *d*, however, will throw the pitman *e* out of line, and as soon as the pitman crosses the axis of the member *d*, it is obvious that the spring *c* is free to act and will give a 55 strong impulse to the switch member *a*, tending to throw the same from one position to the other. As the spring *c* crosses its neutral position, furthermore, and begins to be put under tension, the pitman is ap- 60 proaching the line between the axis of the

member *d* and the pivotal connection with the member *a*, so that a very slight impulse imparted to the disk *d* will, in this case, be largely multiplied in its effect upon the switch member *a*. In other words, at this 70 point in the operation, the disk *d* and pitman *e* are in the nature of a toggle joint, so that, at the end of the movement when the spring *c* is being put under heavy tension, a small amount of power applied to the disk *d* will serve to finish the operation. The spring *d*², therefore, with which the disk *d* is provided, is shown as a coil spring adapted to be wound, from time to time, and does not require a great amount of 80 power, and the said disk may be held in position against the action of the spring *d*² by a tripping device which can be easily operated.

In the construction shown, the disk *d* is provided with an arm *d*³ having engaging surfaces *d*⁴ and *d*⁵ at opposite ends, one or the other of said surfaces normally lying in contact with a stop *f*² on a rocker *f* which is adapted to be acted upon by tripping members *g* and *g*² which are arranged to travel continuously in conjunction with a clock-dial *g*³. The pivotal support *f*³ of the member *f* is so located that, in the rocking movement of the member *f*, produced by the action of the 95 members *g* and *g*², it will carry the stop *f*² in a line substantially radial to the axis of the disk *d*, so that substantially no compression of the spring *d*² is required prior to the 100 release of the member *d*³. At each operation, it is necessary that the disk *d* should make only a half revolution, that is to say, a movement sufficient to either open or close the switch according to the position in which the switch is when the movement takes place. 105 For this purpose, the member *f* is provided with a secondary stop *f*⁴ so located as to come into the path of the member *d*³ just after the stop *f*² has released the said member, but prior to the release of the member *f* by the tripping hand *g*. As the hand *g* travels, therefore, the member *d*³ is first released from the stop *f*² and then arrested by the stop *f*⁴, after which the member *f* is released by the tripping member *g* and restored by means of its spring *f*⁵, so that the engaging surface *d*⁴ will be released in the return movement of the member *f* and the engaging surface *d*⁵ caught by the projection *f*² at the end of half a revolution of the 110 disk *d*. The dial *g*³ is shown as calibrated to represent hours and quarter hours, there being twenty-four main divisions, the clock work being so arranged that the dial will 115 make one revolution for each twenty-four hours.

The actual time is indicated by means of a hand *h*, and the time for operating the switch is determined by the position of the 120 tripping hands *g* and *g*². Taking, for ex- 125 130

ample, the control of a lighting circuit, where it is desired to have the lights in operation from half past five to eleven, and automatically turned on and extinguished, the tripping member g^2 may be set, as indicated on the dial, between numerals 5 and 6, while the tripping hand g is set opposite numeral 11. As shown in the drawing, the dial indicates the time as nine-thirty, and the tripping hand g , which is set to operate at eleven o'clock, is just coming in contact with the tripping lever f . During the travel of the dial through a space indicated by calibrations showing one hour and a half, the lever f will have been rocked on its pivot and released by the tripping hand g , thus causing a half rotation of the disk d , as previously described, and throwing the switch member a from the closed position shown in full lines to the open position shown in dotted lines. The switch will then remain open until the tripping hand g^2 reaches the lever f , and correspondingly trips the same to produce a movement of the switch in the opposite direction.

The disk d is connected by keys d^6 with an extension d^7 from a spring drum d^8 which contains the spring d^2 , the said extension bearing in the front frame plate d^9 , the winding shaft d^{10} extending through the drum d^8 , and bearing at the opposite end in the back frame plate d^{12} . One end of the spring d^2 is connected with the winding spindle which is provided in the usual way with a ratchet d^{13} acted on by a pawl d^{14} pivoted on the frame plate d^{12} .

In order to cushion the shock when the rotation of the disk is arrested by the stops on the lever f , the arm d^9 is shown as loosely supported on the hub of the disk d where it is held by a collar d^{15} , and the ends of said arm bear against plungers d^{16} in sockets d^{17} containing spiral springs. In order to prevent the arm from leaving the ends of the plungers and allowing them to fall from the sockets, a stop d^{18} is employed, against which the other side of the arm bears.

It is essential that the tripping hands g and g^2 which are carried by the clock dial, should be prevented from slipping back, since they act upon the tripping member f in the forward movement, and it is also necessary that they should be easily movable for the purpose of setting the switch for operation at different times. In order to secure the hands against backward movement, the said hands are constructed as shown in Fig. 3, being provided with an annular hub portion g^4 which surrounds a boss formed on the face of the clock dial, the two hands being separated by a washer g^5 , and held in place by a washer g^6 . These washers serve to retain the hands, but do not bear against them with sufficient friction to prevent the forward movement necessary to set them.

The annular portion g^4 is cut, as indicated at g^7 , the cut being inclined in direction, as shown, so that the divided parts will be forced together by any resistance to the backward movement of the hand, thus causing the annular part to bind on the hub. The forward movement of the hand tends to separate the two parts, and to enlarge the annular portion, so that the hands can be moved forward freely.

It is practical with a switch controlling mechanism constructed as above described to utilize an oil insulated switch, that is to say, a switch submerged in oil where currents of very high voltage are to be controlled. In the construction shown in Fig. 4, the casing h for the clock work and tripping mechanism is provided with an oil tank m secured to its under surface, the pitman e^{10} , which corresponds to the pitman e , shown in Fig. 1, extending downward through an opening of the casing into the oil tank. The switch mechanism, which is not shown in Fig. 4, may be identical with that previously described, the pitman e^{10} , however, being somewhat longer in order to provide for the lower position of the switch. The tank m is shown as provided with plugs m^2 and m^3 for putting in and drawing off the oil respectively.

Claims:

1. In a time switch, the combination with a clock movement provided with a traveling calibrated dial; of a pointer stationary with relation thereto to indicate the time; a tripping member mounted on and carried by said dial; a switch member provided with a main operating spring arranged to be under tension when the switch member is in either extreme position; a rotating member connected by means of a pitman with said switch member, said pitman being so proportioned as to be in line with the axis of said rotating member when the switch is in either of its extreme positions; a secondary spring adapted to cause said member to rotate and thereby move said pitman out of line with the axis of said rotating member to permit the operation of the main operating spring; and a stop for said member adapted to be tripped by the clock-work mechanism, substantially as described.

2. The combination with a knife blade switch; of a stiff spring connected with the blade member, said spring being under tension when the blade member is in either its open or its closed position; a spring actuated rotating member connected by a pitman with said switch member said pitman when the switch is open or closed being in line with the axis of said rotating member; a pivotally supported stop member to hold said rotating member stationary against the operation of its spring; a clock dial provided with two adjustable hands adapted to

trip said stop member successively, and a time indicator stationary with relation to said clock dial.

3. In a time switch, the combination with the switch; of a spring for operating the same; a tripping device to control the operation of said spring; a clock dial; and a hand mounted on said clock dial to actuate said tripping device in the travel of the dial, said hand having an annular portion having a diagonal cut therein, substantially as and for the purpose described.

4. The combination with a clock dial provided with a tripping hand; of a pivotally supported tripping member adapted to be operated upon by said hand; a rotating member provided with a spring, said rotating member being caused to make half a revolution through the operation of the tripping device; a disk having a cushioned connection with said rotating member; a pitman connected with said disk; a knife blade switch member connected with said pitman and a spring connected with said switch member and adapted to be under tension when said member is in either of its extreme positions, substantially as and for the purpose described.

5. In a time switch, the combination with a knife blade switch; of a receptacle for oil in which said switch is contained; clock work mechanism carrying a tripping device; a rotary actuating member controlled by said tripping device; a pitman connecting said actuating member with the movable switch member; and a spring connected with said switch member and arranged to be

placed under tension by the movement of the switch member to either its open or its closed position.

6. In a time switch the combination with a knife blade switch; of a receptacle for oil in which said switch is contained; a spring connected with said switch and arranged to be under tension when said switch member is in either its open or its closed position; clock work mechanism carrying a tripping device; means for setting said tripping device to operate at any desired time; a spring-actuated rotary member adapted to be released by said tripping device and permitted to make a half revolution; and a pitman connecting said rotary member with the blade of the switch.

7. In a time switch, the combination with a pivotally supported knife blade switch member; of a spring connected with said member, said spring being under tension except when the switch member is in an intermediate position; a rotary member connected by a link or pitman with said switch member; a second spring acting on said rotary member; a tripping device controlling said rotary member and arranged to permit a half revolution thereof; a clock dial; and adjustable tripping hands carried by said dial to coöperate with said tripping device.

In testimony whereof, I have signed my name to this specification in the presence of two subscribing witnesses.

CHARLES E. CAMPBELL.
